UNITED STATES PATENT OFFICE.

WILLIAM B. GRUBB, OF PHILADELPHIA, PENNSYLVANIA.

LOCK.

Application filed February 3, 1921. Serial No. 442,077.

To all whom it may concern:

Be it known that I, WILLIAM B. GRUBB, a citizen of the United States, residing at Philadelphia, in the county of Philadelphia and State of Pennsylvania, have invented 5 certain new and useful Improvements in Locks, of which the following is a specification.

One object of my invention is to provide 10 an improved lock which will be particularly well adapted to use as a door lock and which can be released after the manipulation of members to set up a predetermined combination of elements and thereby release a selective bolt.

Another object of my invention is to construct the parts in such manner that unless a person knows the combination of manual movements necessary to impart to said members, 20 it is practically impossible, by sense of hearing or touch, even for an expert, to release the lock.

A further object is to make my invention of a strong and durable construction which 25 cannot readily get out of order.

These objects and other advantageous ends which will be described hereinafter, I attain 30 in the following manner, reference being had to the accompanying drawings in which

Figure 1 is a fragmentary elevation of a door having my improved lock thereon,

Figure 2 is an enlarged fragmentary sectional elevation through the door taken on the line 2—2 of Figure 3,

Figure 3 is a sectional plan view taken on the line 3—3 of Figure 2,

Figure 4 is a sectional elevation taken on the line 4—4 of Figure 3,

Figure 5 is a transverse sectional elevation taken on the line 5—5 of Figure 3,

Figure 6 is a perspective view of a shaft which forms a part of my invention,

Figure 7 is a perspective view of a selective bolt which forms a part of my invention,

Figure 8 is a fragmentary perspective view of a main locking bolt constructed in accordance with my invention,

Figure 9 is a face view of one of the selective units of my invention, and

Figure 10 is an edge view of Figure 9.

Referring to the drawings, 11 represents a door; one edge thereof having a cavity 12 in which fits a casing 13. This casing is preferably made rectangular and at one end includes a plate 14 providing a bearing 15 for one end of a shaft 16. The opposite end of

the shaft 16 is mounted in a bearing 17 in a removable front plate 18. This plate 18 may be secured to the door and forms a closure for the front end of the casing. The casing 13 provides a horizontal guideway 19 for an elongated selective bolt or tumbler 20 and a main locking bolt 21. These bolts are arranged side by side; the selective bolt being positioned entirely within the casing while the main locking bolt 21 has a beveled end portion 22 which extends out of a hole 23 in the front plate 18. This beveled portion 22 may enter a keeper of any character (not illustrated) for the purpose of keeping the door locked in the usual manner. The main bolt 21 at its rear end has an angularly bent flange 24 which is backed by a coil spring 25 mounted in a recess 26 in the casing 13. This spring normally tends to push the main bolt 21 into its locking position with the end 22 extending out of the casing. The rear end of the selective bolt 20 is also adapted under certain conditions to engage the flange 24 and when the selective bolt is moved rearwardly, it will move the main bolt 21 inwardly to unlock the door. The main bolt 21 can be moved independently of the selective bolt 20 through the medium of an inner knob 27 which has a spindle 28 provided with an arm 29; said arm being adapted to engage a pin 30, shown in Figure 3, for the purpose of operating the main bolt from the inside of the door independently of any selective mechanism.

The shaft 16 has a longitudinally extending groove or key-way 31 and a plurality of annularly extending grooves 32 spaced apart within its length and forming interruptions in the length of the key-way 31. Each of a number of selective units 33 includes a disk or tumbler 34 and a ratchet wheel 35 detachably secured together side by side by means of screws 36 shown in Figure 4. These units have registering axial holes 37 into which project inwardly projecting lugs 38. The units are adapted to be slid, during assembly, upon the shaft 16 so that the shaft extends through the holes 37 and the lugs 38 can slide through the key-way 31, after which the units can be turned so that the lugs 38 extend into the respective grooves 32 and after the lugs 38 have been turned in the grooves 32 out of alignment with the key-way 31, a key 39 can be inserted within the key way so as to intercept all of the grooves 32. It will be noted that the units 33 can

turn on the shaft 16 through an arc slightly less than 360° or, in other words, from a position in which the lugs 38 abut one side of the key 39 to a position where they abut 5 the opposite side of the key 39.

It will be further noted that by positioning the lugs 38 in the grooves 32 they will be prevented from longitudinal movement with respect to the shaft 16 after the key 10 39 is once inserted. Each of the disks 34 has a concaved notch 40 in its peripheral edge extending from one face to the other. These notches 40 occupy different angular positions 15 relatively to the lug 38 of the same unit in which the notch 40 is formed. This arrangement can be predetermined and under certain conditions hereinafter described the notches 40 of all of the units can be brought into alignment, as shown in Figure 20 4, with the upper edge of the selective bolt 20 therein so that the selective bolt can be slid lengthwise with respect to the units.

The selective bolt 20 has a number of transverse notches 41 in its convex upper 25 edge of lengths substantially equal to the thicknesses of the respective disks so that the disks can extend therein, as shown in Figure 2, and when the notches 40 of the disks are out of register with the selective bolt 20, it will be impossible for the latter to move lengthwise since the opposed ends of the notches 41 will embrace the sides of the disks. The units 33 can be rotated by 30 means of spring-pressed buttons 42 which can be arranged in a row in the door as shown in Figure 1. These buttons 42 are connected to rods 43 which have pawls 44 respectively in alignment with the ratchet wheels 35. Thus for every push of the buttons 40 42 their respective ratchet wheels will be rotated to the extent of one tooth and by knowing previously the setting of the disks relatively to their ratchet wheels, all of the notches 40 can be brought into register with 45 the selective bolt 20 by pushing the buttons a number of times in accordance with the combination of the setting, after which the main bolt 21 can be moved by turning the outside knob 45; said outside knob having 50 a spindle 46 to which is connected an arm 47 adapted to engage a pin 48 on the selective bolt 20. The selective bolt can thus be moved lengthwise into the position shown in Figure 4 and in so doing the inner end 55 of the selective bolt will move the flange 24 of the main bolt 21 and the latter will be withdrawn from its keeper.

Upon the release of the knob 45 the spring 60 25 will move the main bolt outwardly and will also move the selective bolt in the position in which its notches 41 respectively register with the disks 34 of the units and the units can be re-set through the medium of a knurled handle 49 which has a rod 50 leading 65 into the casing 13. The rod 50 has a

helical or worm gear 51 thereon which meshes with another helical or worm gear 52 secured to the shaft 16. In this manner the shaft can be rotated until the key 39 picks up the lugs 38, during the rotation of the shaft, and conveys the various units to their initial starting position, after which the knurled handle can be returned to its initial position as will also be the key 39 and the shaft 16.

As a means for determining the amount of movement necessary to impart to the handle 49, I provide the rod 50 with a pin 53 to strike a fixed projection 54 at the inside of the casing 13. Thus in turning the 75 handle 49 is turned as far as possible in one direction and then turned as far as possible in the opposite direction so as to move the key 39 out of the way of the lugs 38 where it is possible or necessary to again operate the device, the device being thereby reset to a locking position for operation to released or unlocking position as described.

Detent springs 55 are provided on the casing 13 to engage the ratchet wheels 35 and prevent them from over-running due to their inertia. I have illustrated four buttons 42 to operate on four units 33. However, it will be understood that any number of units and buttons can be employed without departing from the principle of my invention. Considering that it is desired to operate the main bolt 21 with the structure as illustrated and the combination of numbers such for example as 9—6—8—4, the left hand button 42 viewed from Figure 1 is pushed inward nine times, the next button six times, the next button eight times and the last button four times. This will move the disks of the respective units into a position in which the notches 40 thereof are in alignment with the plane of the selective bolt 20, then by turning the handle 45, the arm 47 will, by 90 engaging the pin 48, move the selective bolt 20 and the selective bolt 20 due to the flange 24 of the main bolt 21 will engage said flange 24 and move the main bolt 21 and its end 22 inward to an unlocked or released 95 position and the door can be opened.

When the handle 45 is released the spring 25 will return the bolts to their normal positions and by turning the handle 49, the disks and ratchets will be returned to their normal positions. The bolt 21 can be moved independently of the selective mechanism by turning the inner knob 27 and the mere closing of the door will cause the main bolt to be pushed against the spring 25 until the end 22 of the main bolt passes into register with the keeper, after which the spring 25 will move the main bolt into the keeper and the door will be locked.

To guard against any person attempting to open the door by the sense of touch, I

provide each of the disks 34 with one or more decoy recesses 56 which have the shape of the notches 40 but do not extend entirely through the disk. Thus if a person by pushing 5 the buttons 49 feels or hears any action of the selective bolt 20, such for example as would indicate the registry of the selective bolt with a notch, there is practically no possibility of that person securing 10 the combination for the reason that he does not know whether it is one of the proper notches 40 or one of the fooling or deceptive recesses 56 which is in register with the selective bolt 20.

15 While I have described my invention as taking a particular form, it will be understood that the various parts of my invention may be changed without departing from the spirit thereof, and hence I do not limit myself 20 to the precise construction set forth, but consider that I am at liberty to make such changes and alterations as fairly come within the scope of the appended claims.

Having thus described my invention, what 25 I claim as new and desire to secure by Letters Patent is:—

1. Lock mechanism including a selective bolt; selective units for co-acting with said selective bolt; a shaft supporting said selective units and having annular grooves and a key-way interrupted in its length by said grooves, said units having lugs adapted to slide through said key way into said grooves; a key adapted to be inserted within 35 said key-way after the lugs of the selective units have been moved in said annular grooves out of registry with said key-way; and means for operating said selective units whereby they are moved into and out of 40 locking engagement with said selective bolt; substantially as described.

2. Lock mechanism including a selective bolt; selective units for co-acting with said selective bolt; a shaft supporting said selective units and having annular grooves and a key-way interrupted in its length by said grooves, said units having lugs adapted to slide through said key-way into 50 said grooves; a key adapted to be inserted within said key-way after the lugs of the selective units have been moved in said annular grooves out of registry with said key-way; and means for operating said selective units whereby they are moved into and out of locking engagement with said selective bolt, said selective bolt having notches therein in which portions of said selective units can engage to prevent movement thereof, said portions of the selective units having notches for 55 registry with said selective bolt due to the operation of said actuating means whereby the selective bolt can be moved; substantially as described.

65 3. Lock mechanism including a selective

bolt; selective units for co-acting with said selective bolt; a shaft supporting said selective units and having annular grooves and a key-way interrupted in its length by said grooves, said units having lugs adapted to 70 slide through said key-way into said grooves; a key adapted to be inserted within said key-way after the lugs of the selective units have been moved in said annular grooves out of registry with said key-ways; 75 means for operating said selective units whereby they are moved into and out of locking engagement with said selective bolt, said selective bolt having notches there- in in which portions of said selective units can engage to prevent movement thereof, said portions of the selective units having notches for registry with said selective bolt due to the operation of said actuating means whereby the selective bolt can be moved; 80 and independent means for actuating said shaft whereby the selective units can be returned to their normal positions; substantially as described.

4. Lock mechanism including a selective bolt; and selective members movable relatively to the bolt and including members having notches through which a portion of the selective bolt can move, said members having deceptive recesses in opposite sides 95 thereof into which portions of said bolt can be moved when brought into alignment therewith; substantially as described.

5. Lock mechanism including a main bolt; a selective bolt; selective members having notches; means for independently moving said selective members to cause said notches to register with said selective bolt and said selective bolt to move therethrough; means for normally moving the main bolt and selective bolt to locking positions; common means for returning said selective members to their normal positions with the notches out of register with said selective bolt; and means for simultaneously moving both of 105 said bolts to unlocking positions; substantially as described.

6. Lock mechanism including a main bolt; a selective bolt; selective members having notches; means for independently moving said selective members to cause said notches to register with said selective bolt and said selective bolt to move therethrough; means for normally moving the main bolt and selective bolt to locking position; means for returning said selective members to their normal positions with the notches out of register with said selective bolt; means for moving the main bolt or selective bolt to locking positions; and means co-operative between the main bolt and the selective bolt whereby movement of one will simultaneously move the other to an unlocking position; substantially as described.

7. Lock mechanism including a selective

- 4
- bolt; selective units including plain disks, said disks being movable relative to the bolt and having peripheral notches through which a portion of the selective bolt can move, said disks also having decoy notches in the lateral faces thereof into which the selective bolt can move when the notches are out of alignment; substantially as described.
8. Lock mechanism including a selective bolt; selective units for co-acting with said selective bolt; a shaft supporting said selective units and having grooves and a keyway interrupted in its length by said grooves, said units having means to engage the grooves and keyway and entering said grooves through said keyway; means adapted to be inserted within said keyway after said unit means have moved into said grooves to limit the rotation of said units; and stopping means for operating said selective units whereby they may be moved into and out of locking engagement with said selective bolt; substantially as described.
9. Lock mechanism including a selective bolt; selective units for co-acting with said selective bolt; a shaft supporting said selective units and having grooves and a keyway interrupted in its length by said grooves, said units having means to engage the grooves and keyway and entering said grooves through said keyway; means adapted to be inserted within said keyway after said unit means have moved into said grooves to limit the rotation of said units; means for operating said selective units whereby they may be moved into and out of locking engagement with said selective bolt; and means for turning the shaft and simultaneously arranging the selective units in a locking or unlocking position; substantially as described.
10. Lock mechanism including a main bolt; a selective bolt in sliding contact with said main bolt; selective units movable into and out of locking engagement with said selective bolt, said main bolt having a portion for direct abutment with said selective

bolt; means normally projecting the main bolt and moving the selective bolt therewith; and means to hold the main bolt in an unlocked position; substantially as described.

11. Lock mechanism including a main bolt having a flange portion; a selective bolt adapted at one end to engage said flanged portion and having notches therein spaced apart; selective units independently movable; supporting means for said units, said units having portions movable into said notches and including disks having smooth peripheral edges, said disks each having a plurality of decoy notches in one side face and a peripheral recess corresponding in shape to said notches; means for moving said disks to bring the recesses into register with the notches of the selective bolt; and means for moving said selective bolt; substantially as described.

12. Lock mechanism including a main bolt having a flange portion; a selective bolt adapted at one end to engage said flanged portion and having notches therein spaced apart; selective units independently movable; supporting means for said units, said units having portions movable into said notches and including disks having smooth peripheral edges, said disks each having a plurality of decoy notches in one side face and a peripheral recess corresponding in shape to said notches; means for moving said disks to bring the recesses into register with the notches of the selective bolt; means for moving said selective bolt; means co-operative between the main bolt and selective bolt whereby movement of the selective bolt in one direction will move the main bolt to an unlocking position; and means for simultaneously moving said disks to a predetermined position; substantially as described.

In testimony whereof I have signed my name to this specification in the presence of two subscribing witnesses.
